CLAIM

The ornamental design for a combined microphone and mount, as shown and described.

DESCRIPTION

FIG. 1 is an exploded top, front and left side perspective view of a combined microphone and mount showing my new design;

FIG. 2 is an exploded front elevational view thereof;
FIG. 3 is an exploded left side elevational view thereof,
the right side being a mirror image;

FIG. 4 is an exploded rear elevational view thereof;

FIG. 5 is an exploded top plan view thereof;

FIG. 6 is an exploded bottom plan view thereof; and,
FIG. 7 is a top, front and left side perspective view
thereof.
